CLAIM

The ornamental design for eyewear, as shown and described.

DESCRIPTION

FIG. 1 is a perspective view of eyewear showing my new design;

FIG. 2 is a front elevation view thereof;

FIG. 3 is a rear elevation view thereof;

FIG. 4 is a right side elevation view thereof, the left side elevation view being a mirror image thereof;

FIG. 5 is a top plan view thereof; and,

FIG. 6 is a bottom plan view thereof.

The lens of the eyewear of my new design may be transparent, translucent, opaque, or reflective.

The broken lines shown herein are for illustrative purposes only and form no part of the claimed design.
